UNITED STATES PATENT OFFICE.

LESLIE E. HOWARD, OF LA GRANGE, ILLINOIS, ASSIGNOR TO SIMONDS MANUFACTURING COMPANY, OF FITCHBURG, MASSACHUSETTS, A CORPORATION OF MASSACHUSETTS.

ELECTRIC MELTING-FURNACE.

1,076,887.

Specification of Letters Patent. Patented Oct. 28, 1913.

Application filed February 6, 1909. Serial No. 476,480.

To all whom it may concern:

Be it known that I, LESLIE E. HOWARD, a citizen of the United States, residing at La Grange, in the county of Cook and State of Illinois, have invented certain new and useful Improvements in Electric Melting-Furnaces, of which the following is a specification.

This invention relates to electric melting furnaces of what is known as the induction type, and is especially adapted for the melting and refining of metals of the bronze and white metal types, such as copper, brass mixtures, Babbitt metals, aluminum, etc., but may also be used for the melting and refining of iron and steel.

Among the leading objects of my invention are to, as far as possible, reduce the radiating surface of the containing walls forming the melting chamber, greatly increase the cross-section of the molten metal, thereby reducing the resistance and, as a result of this, greatly increase the current, etc., in the secondary; and, instead of disposing the metal bath forming the secondary wholly or partially in an annular chamber of large diameter and small cross-section of the metal, as has heretofore generally been the practice in furnaces of this type, to form the melting chamber in such a manner that the three dimensions of length, breadth and depth of the bath will conform more closely to present practice as found in open-hearth melting furnaces fired by gas, coal, etc. To accomplish these various desirable results, I have discovered that if the secondary is formed only in part of the molten bath to be operated on, substantially one-third of the secondary, and the other portion, substantially two-thirds of the secondary, is formed of a solid mass of metal having a very large cross-section relative to the cross-section of the molten portion of the secondary, the end sought by the invention is accomplished. By this design I further am enabled to place both the primary coil and the secondary, formed in part by the molten bath and in part by the large mass of metal disposed as described, very close to the magnetic field, thus cutting down very largely the magnetic leakage and loss which has heretofore been found a serious objection in this type of furnaces.

In the accompanying drawings, which

represent one practical embodiment of the invention, and in which corresponding numbers and symbols refer to corresponding parts in the different views, Figure 1 is a vertical cross-section of the furnace on the line 1-1 of Fig. 2, and Fig. 2 is a vertical longitudinal section on the line 2-2 of Fig. 1.

Induction furnaces as heretofore designed can be run on a single-phase alternating current only; but for commercial reasons it is often desirable to use multi-phase alternating currents, and this I am enabled to do with my device. While the drawings and description forming a part of this specification refer to a furnace built for two-phase alternating current, the design is readily adapted to a single-phase alternating current by either running the two primary coils in multiple connection from the source of single-phase alternating current supply, or by providing but one primary coil, one magnetic field, and one pair of contact blocks; while to adapt my design to three or more phase currents, it is only necessary to provide as many of the electric systems (comprising the magnetic field, primary coils, secondary winding, and contact blocks) as there are phases to the electrical current supply, each of said systems being in circuit with one phase only of the alternating current supply.

Referring to the drawings, 1 designates a closed magnetic field, formed in the usual manner of thin iron sheets built up with magnetic insulating material between the sheets in the manner usually employed in the construction of electrical transformer cores.

2 designates the two primary windings which are placed around the two lower limbs of the magnetic field 1, these primary windings being supplied by any suitable source of alternating, pulsating or intermittent current of electricity, but more preferably two-phase alternating current, which may be supplied by a generator, as indicated diagrammatically at 2^a. The solid portion of the secondary circuit is made up of a pair of preferably dense castings of some suitable material such as copper, iron or steel, copper being preferable on account of its low electrical resistance properties. Each of these castings comprises a bottom horizon-

tal member 3 and outwardly inclined or flaring sides 4. These latter are provided with end flanges indicated at 4^a in Fig. 2, to which flanges are securely attached, as by bolts 5, current-conducting blocks 6 of any suitable material, in some special cases graphite, but preferably of cast steel with a high melting point. It will be observed by reference to Fig. 1 that the blocks 6 have an extended contact surface with the conductors 4, while the opposite surface, in contact with the bath, indicated at 7, is relatively small. The blocks 6 are provided with water ducts or pipes 8 having end connections indicated at 8^a and supplied with water through a hose 9 for the purpose of preventing the blocks at their surfaces of contact with the bath from becoming molten.

Fitted around the upper and inner faces and ends of the contact blocks 6 is a housing forming, with said blocks, a containing chamber for the bath. This housing comprises a bottom wall 10 lying between the blocks 6, side walls 11 superposed on the blocks 6, and end walls 12, one of which latter is preferably formed with a pouring spout 13, these several parts being preferably, and as shown, integral. This housing or casing forming, with the contact blocks 6, a containing chamber for the bath, is of any suitable refractory material, strengthened somewhat and made more durable by a casing 14 of sheet iron or other suitable material surrounding the end and side walls thereof.

Between the bottom 10 of the melting chamber and the upper limb of the magnet 1 are disposed a series of pipes or ducts 15 suitably connected at their ends by return bends 16 and supplied with a cooling medium as water, either independently or from the pipes 8 through a connecting hose or pipe 17 (Fig. 2); the purpose of these pipes or ducts being to prevent the temperature in the magnet 1 from rising above a desirable limit as a result of radiation of heat from the molten bath 7.

The melting chamber is conveniently closed at the top by a cover 18 of refractory material, which cover may be formed in sections, if desired, for convenience in handling, and is preferably strengthened on top by ribbed metal frame-plates 19 preferably made in two sections with a joint 55 connected by bolts 20, said joint being insulated by suitable material such as asbestos, as shown at 21, to prevent any shunting of the induced current around the cover. The cover is locked in place on the melting chamber by any suitable or convenient means, as by links 22, pivoted at 23 to the lower ends of vertical loops 24 that are integral with or secured to the metal frame sections 19 for the application of the hooks of an overhead crane, the links 22 engaging notched

ears 25 on the metal casing 14 and being apertured to receive suitable locking wedges or cotters 26.

The apparatus is supported with capacity for a pivotal or tilting movement to deliver the molten bath on a pair of parallel iron beams, herein shown as inwardly facing channels 27, to which the bottom member 3 is secured by suitably insulated bolts shown at 28. The beams 27, in turn, are strongly riveted to a pair of depending arms 29, the upper ends of these latter having trunnions 30 rotatably journaled in bearings 31 on the upper ends of a pair of standards 32. The lower limb of the magnet 1 rests on cross-bars 33 that are riveted at their ends to the lower sides of the beams 27.

A power device for tilting the apparatus sufficiently to pour the molten bath through the spout 13 into a ladle or other suitable receptacle is herein shown, the same comprising the cylinder 34 containing a piston 35, the piston-rod 36 of which is pivotally connected at 37 with an ear or lug 38 formed on a cross-bar 39 riveted to and between the ends of the longitudinal bars 27. The cylinder 34 is pivoted at its lower end at 40 to a supporting base 41, so as to be capable of rocking in the same direction as the furnace. The cylinder is provided at its upper and lower ends with ducts 42 and 43, respectively, which lead into the circular casing 44 of a four-way valve 45, which latter is provided with an operating handle 46.

47 designates a supply duct leading from a source of compressed air or any other suitable motive fluid, while 48 designates an exhaust duct on the opposite side of the valve casing from the supply 47. A pair of oppositely curved ducts 49 and 50 formed through the valve-body serve to connect the supply and exhaust ports 47 and 48 with the cylinder ducts 42 and 43, said ducts 49 and 50 alternately acting as supply and exhaust ducts, according to the position of the valve.

In the position of the valve shown in Fig. 2, the motive fluid has been admitted to the upper end of the cylinder and exhausted from the lower end thereof, thus returning the furnace from tilted to horizontal position. By lowering the valve handle 46 so as to transpose the connections of the ducts 49 and 50, the motive fluid will be admitted to the lower end, which effects the tilting of the furnace and the pouring of the contents.

In operation, molten or solid metal is charged into the melting chamber in such a manner as to form an electrical connection between the contact blocks 6. If the metal is charged solid, it is advisable to cut the bars of such a length that they will readily bridge over the space between the blocks 6, forming a contact with them. After the melting chamber is properly charged with

molten or solid metal, as described, the electric current is caused to flow through the primary coils 2, setting up a strong magnetic flux in a magnetic field 1. The magnetic flux in that portion of the magnetic field 1 which is immediately surrounded by the secondary circuit formed in part by the permanent members 3, 4 and 6, and in part by the molten bath 7, causes an electric current of very low voltage but extremely high current density to be generated, partly in the molten metal and partly in the permanent conductors represented by the parts 3, 4 and 6, and that portion generated in the parts 3, 4 and 6 is caused to flow through the bath 7 by contact of the said bath with the blocks 6. The temperature of the bath may be regulated by controlling the current passing into the coils 2, this control being effected by any of the well known means, such as inductive resistance induced as shown diagrammatically at 2^b. After the metal comprising the bath 7 is sufficiently melted or otherwise treated, the connection of the coils 2 with their source of electric energy is broken, and the electrical action of the apparatus thereby ceases. The charge is then poured by manipulation of the valve of the power tilting device, as already described, and returned to normal position after the pouring. It is usual to pour only about from 50 per cent. to 75 per cent. of the contents of the melting chamber, the remainder being left for convenience in closing the secondary circuit between the blocks 6 and fresh cold or molten metal, which is then placed in the melting chamber, and the process as above described repeated.

Believing myself to be the first to disclose a melting furnace of the character described wherein the secondary circuit is formed partly of molten metal and partly of a permanent conductor arranged in series, I do not limit the invention to the particular apparatus herein shown and described, as it is evident that the same may be considerably modified by those skilled in the art without involving any departure from the underlying principle, or sacrificing any of the advantages, of the invention.

I claim:

1. An electric melting furnace having a multiphase transformer with a plurality of secondary circuits each formed in series partly by a permanent conductor, said secondary circuits adapted to be completed by the body of metal subjected to the action of the furnace.

2. In an electrical melting furnace, the combination of a transformer core, primary windings on said core, a trough-shaped receptacle of refractory material mounted on said core, electrode blocks extending at opposite points through the side walls of said receptacle and having inner areas in con-

tact with material within the receptacle to be melted, and heavy conductive U-frames looping through said transformer core and connecting with said electrode blocks and forming with said electrode blocks and the material within the receptacle substantially short circuited secondary circuits. 70

3. In an electrical melting furnace, the combination of a transformer core, primary windings on said core, a trough-shaped receptacle of refractory material mounted on said core, electrode blocks extending at opposite points through the side walls of said receptacle and having inner areas in contact with material within the receptacle to 80 be melted, and heavy conductive U-frames looping through said transformer core and connecting with said electrode blocks and forming with said electrode blocks and the material within the receptacle substantially 85 short circuited secondary circuits, the contact areas of the electrode blocks with the material within the receptacle being restricted whereby the heavy current flow through said secondary circuits is concentrated through the material to be melted. 90

4. In an electrical melting furnace, the combination of a transformer core, primary windings on said core, a trough-shaped receptacle of refractory material mounted on 95 said core, electrode blocks extending at opposite points through the side walls of said receptacle and having inner areas in contact with material within the receptacle to be melted, heavy conductive U-frames looping through said transformer core and connecting with said electrode blocks and forming with said electrode blocks and the material within the receptacle substantially 100 short circuited secondary circuits, and a support on which said transformer core is 105 tiltably supported.

5. In an electric melting furnace, the combination with a tilttable support, of a solid metal series portion of a secondary circuit 110 mounted thereon and having upwardly extending sides provided with contact blocks, a rectangular core member embracing the intermediate base portion of said secondary, a primary coil surrounding one limb of said 115 core member, and a receptacle of refractory material surmounting said secondary and formed with apertured side walls through which said contact blocks project whereby to form contact with the material to be operated upon in said receptacle. 120

6. In an electric melting furnace, the combination with a tilttable support, of a solid metal series portion of a secondary circuit mounted thereon and having upwardly extending sides provided with contact-blocks, 125 a rectangular core member embracing the intermediate base portion of said secondary, a primary circuit coil surrounding one limb of said core member, a receptacle of refrac- 130

tory material surmounting said secondary and formed with apertured side walls through which said contact blocks project whereby to form contact with the material to be operated upon in said receptacle, and means for circulating a cooling medium between said receptacle and core member.

7. In an electric furnace, the combination, with a furnace basin, of an induction coil 10 whose secondary consists of a fused portion of the bath within the basin, and an unfused conductor outside of and below the basin.

8. In an electric furnace, the combination, with a furnace basin, of an induction coil

having an annular secondary circuit consisting partly of a fused portion of the bath within the basin, and the remainder of an unfused conductor outside of and below the basin of relatively high conductivity compared with the fused portion of the circuit. 15 20

In testimony that I claim the foregoing as my invention, I have hereunto subscribed my name in the presence of two witnesses.

LESLIE E. HOWARD.
